UNITED STATES PATENT OFFICE.

WILLIAM CAROL HUDSON, OF KEATING, OREGON.

HAYSTACKER.

Application filed August 28, 1922. Serial No. 584,820.

To all whom it may concern:

Be it known that I, WILLIAM CAROL HUDSON, residing at Keating, county of Baker, State of Oregon, citizen of the United States, have invented certain new and useful Improvements in Haystackers, of which the following is a specification.

The object of my invention is to provide a novel hay-stacker, with improved means 10 for adjusting the swing of the load to the height desired, according to the increasing height of the stack; means for tripping the hay-fork to drop the load; and means for guiding the horizontal swing of the fork 15 supporting frame.

The invention is graphically disclosed in its preferred form in the accompanying drawings, forming part of this specification, like reference characters designating corresponding parts throughout the several views. Briefly described:

Figure 1 is a view in side elevation of my hay-stacker.

Figure 2 is a top plan view thereof; 25 Figure 3 is a horizontal section on the line 3—3, Fig. 1, looking in the direction indicated by the arrows thereon;

Figure 4 is a fragmentary view in elevation, partly in section, of the hay-stacker; 30 and

Figure 5 is a view in perspective of the hay-stacker, parts being broken away.

Referring, now, in detail to the drawings:

35 1, 1 designates base-members, and 2, 2 transverse base-members secured thereto, as shown at 3. 4 designates an intermediate transverse base-member, likewise secured, at its ends, to the base-member, 1.

40 5 designates a mast rotatably supported upon the base-member 4.

Bars 6, 6 rise convergently from one of the base-members 1, and are secured, at their upper ends, to an angle-plate, comprising 45 the flanges 7 and 8, to which latter flange the bars 6, 6 are secured, as shown at 9. A pivot-pin 10 passes through the flange 7 and loosely into the top of the mast 5.

50 Bars 11, 11 rise convergently from the other base-member 1, and may be secured, at their upper ends, as shown at 12, to a slat 13 extending transversely of and secured at its ends to the bars 6, 6.

55 Extending transversely of the bars 11, 11 is a slat 14, to which the ends of a strap

15, encircling a circumferential portion 16 of the mast 5, are secured.

Also convergently rising from the base member 1 to which the bars 6, 6 are secured are two similar bars 17, 17, to which a track 60 18 is secured, by means of tongues 19, 19 carried by the latter. The track is a substantially U-shaped strip of metal, as shown. The track may be provided with additional tongues 20, 20 secured to a slat 21, which is, 65 in turn, secured, at its ends, to the bars 17, 17. Preferably, the tongues 19, 19 and 20, 20 are integral with the track, as shown, so that it is possible to stamp the track with its tongues out of a single piece of sheet 70 metal.

Rigidly secured to the lower end of the mast 5, as by means of a pair of parallel, spaced plates 22, 22, is a bar 23, for a purpose presently appearing.

75

Pivots secured to the mast 5, as by means of the pivot pin 24, is the supporting carriage of the lifting fork of the hay-stacker. The supporting carriage while it may be of any preferred form, is herein shown as 80 comprising bars 25, 25, and transverse slats 26, 26'. As shown, the pivot pin 24 passes through said bars 25, 25, toward one end thereof.

The fork is of the conventional form and 85 comprises, as usual, a series of spaced parallel teeth 27. The fork is pivotally secured to the bars 25, 25 in any suitable manner, preferably by means of straps 28, 28 secured to one end of the bars 25, 25, and provided, 90 at their free extremities, with eyes 29, 29, passing through which are staples 30 carried by a transverse slat 31 secured to the fork teeth 27, toward one end thereof.

The lifting mechanism for the fork will 95 now be described:

Pivots journaled in the bars 25, 25, toward the end thereof to which the fork is secured, is a rod 32.

One end of a cable 34 is secured to the 100 pulley 33, the cable passing over a pulley 35, carried at the upper end of complementary arms 36, 36, secured at one end to the mast 5 by bolts 37, and over the pulley 33, thence over a pulley 35' carried between the arms 105 36, 36, thence through an opening 38' in the mast 5, and over a pulley 38 in said opening, thence downward over a pulley 39 carried between the plates 22, 22 and thence 110 between pulleys 40, 40 carried at the

free end of the arm 23. Thus, the operator, by pulling upon the end of the cable 34 which projects between the pulleys 40, 40, will exert an upward pull on the rod 5 32, thereby raising the supporting carriage 25, 25 on its pivot 24, the carriage carrying with it the fork. During the initial pull of such lifting movement, the carriage 25, 25 and the fork rise vertically without any side- 10 wise swinging movement, by reason of the fact that the upper portions of the cam track 18 are in a vertical plane, such vertical portions of the cam track extending from the tip *a* to the point *b*. From the point *b* the 15 track is bent sidewise, as is shown by the shading thereon in Fig. 1. As the roller 41 reaches the lower end of the vertical portion of the track 18, it passes along the bent portion of the track, permitting the mast 5 to 20 be swung around, swinging around with it the carriage 25, 25 and the fork carried thereby.

The roller 41 is secured on one end of a bifurcated member 42, the furcations 43 of 25 which are pivotally secured at the ends thereof, as shown at 44, to the mast 5. Between the furcations 43, 43 of the member 42 is projected an arm 45 pivotally secured at 30 its upper end, as shown at 46, to one end of the carriage beams 25, 25. The other end of said lifting arm 45 is provided with a longitudinally extending series of openings 47, through any one of which, and through 35 aligned openings 48 in the furcations 43, 43, a pin 49 may pass. By this means the lifting arm 45 is adjustably secured to the member 42. In this manner, also, the lateral swinging of the rod on the fork may be adjusted to the height desired, according to the 40 increased height of the stack.

It should be understood that the mast 5 is 45 rotatable in one direction only; because one of the arms 36, rigid with the mast, contacts with the adjacent upright frame bar 6, as will be understood by reference to Fig. 5, so that rotary movement of the mast in a direction to move the roller 41 away from the cam track 18 is prevented.

The invention comprehends suitable tripping means for the fork, whereby the same 50 may be released at the proper time, so as to dump the load. The preferred form of such mechanism is shown in the drawings and will now be described:

Secured to an eye 50, carried intermediate 55 of the length of a transverse bar 51 of the fork, is a cable 52 passing over a guide-pulley 53 carried by the slat 26', and thence upward over a similar pulley 54 carried in an opening 55 in the mast 5, thence downward over a third pulley 56, likewise carried in a similar opening 57 in the mast 5, thence through said opening 57 downward to an eye in the upper end of the segment 58 pivotally secured, as shown at 59, to a bracket 60

secured, as at 61, to the mast 5. The segment 58 is preferably provided with stops, comprising lugs 62, 62, suitably positioned thereon for limiting the upward movement of the segment. The segment may be provided with means for securing a more limited swing thereof than is afforded by the lugs 62, 62, and in this instance I have shown the segment as provided with a series of openings 63, through any one of which a pin (not shown) may pass, as is obvious, such pin functioning as does the lower stop 62, to contact with the bracket 60 in the upward movement of the segment, thereby limiting the upward swing thereof. The segment 58 is provided with a notch 64 normally engaged by the beak 65 of a tripper 66 pivotally secured, as shown at 67, to the bracket 60.

In operation, after the load has been lifted on the fork of the hay stacker and the mast 5 has been swung around with the carriage 25, 25, so as properly to position the fork over the stack, the operator pulls upward upon the tripper 66, thus releasing the beak 65 thereon from the notch 64, whereupon the weight of the load upon the fork immediately tilts the fork downward, thus pulling upon the cable 52 and oscillating the segment 58 upward on its pivot 59, the swinging movement of the segment and, consequently, the degree of drop or tilting movement of the fork, being governed by the lower stop 62, which contacts with the bracket 60.

It may be explained that the lower stop 62 is so positioned on the segment 58 as to permit the fork to swing downward, from a horizontal to a vertical position. However, by placing a pin in one of the openings 63 of the segment 58, it will be seen that, when the tripper 66 is released from engagement with the segment 58, the fork will move from a horizontal position to an inclined position, with reference to the ground, and will not drop to a perpendicular position with reference to the ground, thus permitting the load to slide off of the fork at the desired angle. In other words, by the construction described, the load raised on the fork may be dropped straight down or may be permitted to slide off it at an angle.

Suitable means are provided for automatically returning the fork and segment 58 to normal position, after dropping of the load from the fork, as just described, and, in this instance, such means comprises a coiled spring 68 secured at one end to the segment and at its other end to an eye 65 carried by the mast 5.

It will thus be seen that my invention comprehends a hay stacker of novel construction, embodying novel instrumentalities for permitting an initial vertical lifting of the fork and a subsequent bodily

swinging movement thereof in a horizontal plane; and novel instrumentalities for permitting the fork to drop either vertically or to an inclined position; and, finally, novel 5 instrumentalities for adjusting the lateral swinging of the load to the height desired according to the increased height of the stack.

What I claim to be new and desire to secure by Letters Patent is:

- 10 1. In a hay stacker, the combination with a vertical revoluble mast, of a substantially U-shaped strip of metal, constituting a cam-track, fixed relative to the mast, an arm pivotally secured to said mast and carrying a roller moving on said cam-track, a hay-fork supporting carriage pivotally secured to said mast, and a connection between said supporting carriage and said arm.
- 15 2. In a hay stacker, the combination with a vertical revoluble mast, of a substantially U-shaped strip of metal, constituting a cam-track, fixed relative to the mast, an arm pivotally secured to said mast and carrying a roller moving on said cam-track, a hay-fork supporting carriage pivotally secured to said mast, and a connection between said supporting carriage and said arm and adjustably secured to the latter.
- 20 3. In a hay-stacker, the combination with a vertical revoluble mast, of a substantially U-shaped strip of metal, constituting a cam-track, fixed relative to said mast, an arm pivotally secured to said mast and carrying a roller moving on said cam-track, a hay-fork supporting carriage pivotally secured to said mast, and a connection between said supporting carriage and said arm and adjustably secured to the latter.
- 25 4. In a hay stacker, the combination with a vertical revoluble mast, of a substantially U-shaped strip of metal, constituting a cam-track, fixed relative to the mast, an arm pivotally secured to said mast and carrying a roller moving on said cam-track, a hay-fork supporting carriage pivotally secured to said mast, and a connection between said supporting carriage and said arm.
- 30 5. In a hay stacker, the combination with a vertical revoluble mast, of a substantially U-shaped strip of metal, constituting a cam-track, fixed relative to said mast, an arm pivotally secured to said mast and carrying a roller moving on said cam-track, a hay-fork supporting carriage pivotally secured to said mast, and a connection between said supporting carriage and said arm.
- 35 6. In a hay stacker, the combination with a vertical revoluble mast, of a substantially U-shaped strip of metal, constituting a cam-track, fixed relative to said mast, an arm pivotally secured to said mast and carrying a roller moving on said cam-track, a hay-fork supporting carriage pivotally secured to said mast, and a connection between said supporting carriage and said arm.

one end of said carriage, and means for tripping said hay fork to permit the same to drop under the weight of the load thereon. 40

4. In a hay stacker, the combination with a vertical revoluble mast, of a substantially U-shaped strip of metal, constituting a cam-track, fixed relative to the mast, an arm pivotally secured to said mast and carrying a roller moving on said cam-track, a hay-fork supporting carriage pivotally secured to said mast, and means for tripping said hay fork to permit the same to drop under the weight of the load thereon, said tripping means comprising a pivoted segment and a trip member normally engaging the segment. 45

5. In a hay stacker, the combination with a vertical revoluble mast, of a substantially U-shaped strip of metal, constituting a cam-track, fixed relative to the mast, a hay-fork supporting carriage pivotally secured to said mast, a hay fork pivotally secured to one end of said supporting carriage, and means for tripping said hay fork to permit the same to drop under the weight of the load thereon, said tripping means comprising a pivoted segment and a trip member normally engaging the segment, said segment being carried by a bracket and provided with a series of openings, and a pin engageable with any one of said openings and contacting with said bracket to limit upward movement of said segment. 55 60 65 70

In testimony whereof I hereunto affix my signature.

WILLIAM CAROL HUDSON.
